(57) **CLAIM**

The ornamental design for a cosmetics caddy, substantially as shown and described.

DESCRIPTION

FIG. 1 is a perspective view of a cosmetics caddy showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

Broken lines of FIGS. 6 and 7 illustrate portions of the cosmetics caddy that form no part of the claimed invention.
